UNITED STATES PATENT OFFICE.

ROBERT A. SCOTT, OF BOSTON, MASSACHUSETTS, ASSIGNOR TO THE PEERLESS KNITTING MILLS COMPANY, OF BOSTON, MASSACHUSETTS, A CORPORATION OF MAINE.

UNDERWEAR.

1,274,354.

Specification of Letters Patent. Patented July 30, 1918.

Application filed November 18, 1913. Serial No. 801,613.

To all whom it may concern:

Be it known that I, ROBERT A. Scott, a citizen of the United States, residing at Dorchester, Boston, in the county of Suffolk and State of Massachusetts, have invented certain new and useful Improvements in and Relating to Underwear, of which the following is a specification.

This invention relates to improvements in under-garments or underwear, more particularly to garments known as closed crotch union underwear.

Its object is to provide a garment having a permanently closed crotch and desirable characteristics of construction both of the drop-fall or drop seat and the side opening effect union garment, which are so correlated that but a single button is required to effect a complete closure of the garment and to hold the back flap or drop-fall in closed position, and which co-act when the back flap is unbuttoned to afford an ample posterior opening free from any binding action upon the body in operation, and when said back flap is buttoned, to provide a garment with positive closing features which prevent gaping.

Other objects of my invention will be obvious to those skilled in the art from the disclosure of a garment embodying it, which I have herein made for the purpose of illustration.

Figure 1 is a front view of a garment embodying my invention.

Fig. 2 is a back view thereof, the posterior opening being closed and the legs of the garment being broken away.

Fig. 3 is a view similar to Fig. 2 with the parts of the garment thrown back to form the posterior opening.

Fig. 4 is a bottom plan view of the garment as shown in Fig. 2.

Figs. 5, 6, 7 and 8 are developed views of the parts constituting the garment, the sleeve parts being omitted and the legs being broken away.

In the drawings, 1 represents the body of a garment having a front 2, back 3 and leg portions 4, 5. The sections or parts just described may be of any well known and

suitable construction or formation, each in itself constituting no part of my present invention. The garment illustrated is knit or woven in a well known manner.

The back of the garment is formed or cut to have a V-shaped opening with the point of the V uppermost and nearest the waist line. The lines 6 and 7 converge to form this opening, each extending from the point 8 at the top of the V to points 9 and 10, respectively, in the adjacent inside leg seams of the garment.

11 is a triangular shaped gore, preferably made of material possessing some elasticity. It is fitted into the V-shaped opening and secured at its adjacent sides to the adjacent edges 6 and 7 of the garment body.

12 is a gore or back flap having an upper free edge 12', right side free edge 12^a and left side secured edge 12^b. This gore is cut so as to have a tongue 12^c at its lower left-hand corner and a V-shaped extension 12^d between the tongue 12^c and the right side free edge 12^a. The left side edge 12^b, including the left side edge of the tongue 12^c, is sewed to the edge 7 between the points 8 and 10. The other edge of the tongue 12^c is sewed to the left leg section along the line 10' and the extension 12^d is carried under and forward and secured along the lines 10' and 9' at either side of the point of intersection of the leg sections at the crotch, so as to form a permanently closed crotch. The back flap 12 may be cut quite full adjacent its lower right hand edges or the parts which form the permanently closed crotch, so as to preclude the possibility of the garment binding at these points, this fullness of cut not being sufficient to cause gaping.

13 is a triangular shaped gore extending preferably from a point adjacent to the lower right-hand corner of the triangular gore 11 into the V-shaped opening adjacent the upper end of the right leg section. It is sewed at its right-hand edge to the body of the garment along the line 6 between the gore 11 and the point 9 in the right leg seam, and along the line 9' between the point 9 and a point 9^a which may be slightly above the point 9^b at which the lower right hand

corner of the back flap 12 is attached to the right leg section. This will insure that the back flap and gore 13 will together constitute a perfect closure for the posterior opening of the garment and that in operation the back flap 12 will overlap the gore 13.

At its upper right-hand free corner the back flap 12 is provided with a suitable fastening device for fastening it to the body of the garment. For the purpose of illustration I have shown this to be a button and buttonhole connection.

14 is a button hole in the back flap, and 15 is a button secured to the body of the garment.

In order to expose the posterior opening it is only necessary to unbutton the one button 15 which normally holds the back flap 12 as a closure therefor, whereupon the right-hand free corner of the back flap may fall downwardly and be moved or swung to the left about the line 7. The free edge 13' of the gore 13 may be swung or moved to the right, and since the triangular gore 25 11 is formed of elastic material or material possessing some elasticity, the distance between the lines 6 and 7 adjacent the posterior opening may be increased against the said elasticity of the gore 11. This insures a 30 posterior opening of ample proportions and one, the boundaries of which, will not bind the body of the wearer. When it is desired to close the posterior opening, the upper end of the gore 13 and the upper left-hand corner 35 of the back flap 12 are drawn toward each other by the contraction of the lower end or edges of the triangular gore 11, as soon as the gore 11 is free to contract, and the free edge 13' of the gore 13 positions itself 40 against the body and underneath the free edge of the back flap 12. Thereupon the free upper corner of the back flap 12 may be again buttoned to the button 15.

The parts constituting my garment are 45 constructed and arranged so that the posterior opening may be exposed without the necessity of operating the fastening means for the back flap 12. This is accomplished merely by pushing to the left the free edge 50 of the back flap 12 and to the right the free edge of the gore 13. I prefer, however, to provide the garment with suitable fastening means, such as herein described and illustrated, in order that the upper free corner 55 of the back flap 12 may be readily unfastened and thrown back in the event the garment shrinks at any time, or for any other desired purpose.

To those skilled in the art of making devices of the class described, many alterations in construction and widely differing embodiments and applications of my invention will suggest themselves, without departing from the spirit and scope thereof. My disclos-

ures and the description herein are purely 65 illustrative, and are not intended to be in any sense limiting.

What I claim is:—

1. An undergarment having a body including leg sections, formed with an opening the walls of which converge to a point adjacent the waist line and to points in each of said leg sections, respectively, a back flap secured at one side edge to said body between the point of said opening adjacent said waist line and said point in one of said leg sections, and having an extension carried forward and secured to said body between the leg sections to form a permanently closed crotch, the upper edge and other side edge 80 of said back flap being free, a gore secured to the other side wall of said opening and having a projection extending into and secured to the converging walls of said opening in the adjacent leg section, the said back 85 flap when in closed position overlapping the free edge of said gore and a fastening device between the upper free corner of said back flap and the body.

2. An undergarment having a body formed 90 with a permanently closed crotch, and an opening bounded by lines which converge to a point near the waist of the garment, a gore secured at either side to the adjacent edge wall of said opening near its upper end, 95 the lower edge of said gore forming the upper boundary of the posterior opening for the garment, a back flap secured at one side edge to said body and arranged to close said posterior opening, and a fastening device 100 for detachably connecting the free side of said back flap to the body.

3. An undergarment having a body formed with a permanently closed crotch, and an opening bounded by lines which converge to 105 a point near the waist of the garment, a triangular gore secured at either side to the adjacent edge wall of said opening near its upper end, the lower edge of said triangular gore forming the upper boundary of the posterior opening for the garment, a back flap secured at one side edge to said body and arranged to close said posterior opening, and a fastening device for detachably connecting the free side of said back flap to the 110 body.

4. An undergarment having a body formed with an opening, a gore secured above its lower edge to the adjacent walls of said opening, the lower edge of said gore forming the upper boundary of the posterior opening for the garment, a back flap secured at one side to said body, arranged to close said posterior opening and forming at its lower end with said body a permanently 120 closed crotch, and a fastening device for detachably connecting the free side of said back flap to the body.

5. An undergarment having a body with a posterior opening, one side of which is formed by the free edge of a gore, the upper end of which is formed by the free edge of another gore, and the other side of which is bounded by the edge of a back flap secured to the body of the garment, said back flap at its lower end forming with the body a permanently closed crotch and having its upper and outside edges free, and a fastening device between the upper outside corner of the back flap and the body. 10

In testimony whereof I affix my signature, in the presence of two witnesses.

ROBERT A. SCOTT.
